UNITED STATES PATENT OFFICE.

GEORGE D. BURTON, OF NEW IPSWICH, NEW HAMPSHIRE.

STOCK-CAR.

SPECIFICATION forming part of Letters Patent No. 374,824, dated December 13, 1887.

Application filed March 22, 1887. Serial No. 231,980. (No model.)

To all whom it may concern:

Be it known that I, GEORGE D. BURTON, a citizen of the United States, residing at New Ipswich, in the county of Hillsborough and State of New Hampshire, have invented certain new and useful Improvements in Stock-Cars, of which the following is so full, clear, and exact a description as will enable others skilled in the art to which my invention applies to make and use the same, reference being had to the accompanying drawings, in which—

Figure 1 is a side elevation of a car in which are embodied my improvements. Fig. 2 is a top plan view of the same with the top of the car removed. Fig. 3 is a vertical transverse section of the same. Fig. 4 is also a vertical section showing a water-tank in position. Fig. 5 is a detail view of the sliding troughs and hollow posts and guides therefor. Fig. 6 is a top plan view of the device shown in Fig. 5. Fig. 7 is a section of the tank shown in Fig. 4, and this view is taken on the line *x x* of Fig. 4. Fig. 8 is a vertical section of the car, showing a sliding trough and its counterbalancing weights. Fig. 9 is a detail view of the locking device for holding the trough in position. Fig. 10 is a transverse vertical section of my car, showing a partition in the water-tank to counteract the force of the water as the car is swayed from side to side. Fig. 11 is another view of a locking device for holding the trough in position when it is down. Fig. 12 is a detail view of a portion of the top of the car, showing suitable staples for hitching and other purposes. Fig. 13 is a transverse section of the car, showing most clearly the pipe *D*, which is used for a water-conductor and a ventilating-flue, and also to receive the cables and weights of the sliding troughs. Fig. 14 is an additional detail of the same.

The object of my invention is to construct a stock-car in which the stock may be accommodated to the best possible advantage, and at the same time leave the greatest amount of space in the car for the attendant and for the storing of articles which it may be desired to carry with the stock, such as hay, grain, harnesses, saddles, and other appurtenances.

Another object of my invention is to construct a car in which the water may be carried in the tank within the car without liability

of racking or straining the car to any great extent in rounding curves, crossing switches, and passing over frogs, &c.

55

Another object of my invention is to construct a car in which the animals may be easily taken from their stalls, in order to facilitate the cleaning of the stalls and the grooming of the animals in the car.

Co

Another object of my invention is to construct a car which shall be complete in every respect, and at the same time have few or no detachable fixtures exposed within the car.

Heretofore great difficulty has been experienced in all improved stock-cars, because of their internal fixtures being exposed to view and easily removable, which resulted in their being robbed of their fixtures by the thieves which abound about large freight-depots and stock-yards.

65 In the accompanying drawings, *A* designates the main car-body.

B is a central partition which divides two central series of stalls, *C C*, which stalls have 75 at their outer ends a trough, *E*, which trough slides vertically in upright standards *D*, which standards are made hollow to receive and accommodate weights *F F*, which are supported by cords *G G*, one end of which cords is secured to the trough, while the other end supports the weight *F*. These troughs are adapted to slide freely within the guides *H H* on the outer edges of the vertical posts *D*. The troughs are securely locked in position by 80 locking devices *J*, one of which consists of an ordinary pin having a cord or chain attached thereto, while the other consists of an eccentric gravity-latch pivotally secured in such a position that it will fall by its own gravity 85 across the slot *H* and hold the trunnion *e* of the trough against accidental displacement vertically.

90 *K* designates a water-tank which is adapted to receive and accommodate from six to ten barrels of water, as occasion may require, and is also adapted to confine the water in such a way as to prevent the straining or wrenching of the car to any appreciable extent. This is effected by constructing it conical, making it 100 taper toward its outer ends, as shown in Fig. 4, or by providing it with a central partition, *K'*, provided with perforations *k k*, as shown in Fig. 10. The perforated partition *K'* is se-

cured to the bottom of the tank by bolts or rivets $l l$, and is secured at its upper outer ends by other bolts, l' , which pass through the perforation m in a lug, n , on the plate K . The tank should be firmly braced and held in position within the car, and this is effected by diagonal stays $L L$ when the tank is made as shown in Fig. 10, or by the supports $L' L'$, which pass around the lower end of the tank, as shown in Fig. 4 and in detail in Fig. 7.

By reference to Fig. 2 it will be observed that the stock are taken into the car and backed into the stalls before the troughs are lowered in place in front of the animals. The troughs will hold the animals in place and prevent them from getting out; but when additional security is desired the chains or other cables $a a$ may be used as an additional protection against accidental escape of the animals from the stalls. Another advantage of these sliding troughs, and one which is greatly appreciated by shippers, is that it enables the shipper to slide the trough up entirely out of the way of the animal at such times as it is desirable to have the animal lie down. The trough can thus be shoved up to the top of the car and the animal can lie down and get up at will without liability of bumping its head or becoming bruised about its head and shoulders, as is quite liable to be the case, owing to the constant and irregular motion of the cars and the strangeness to the animal of the situation, as the chains $a a$ will be all that is necessary to hold the animal against escape from the stall.

The water tank is provided with a supply-pipe, M , which has a cock or faucet, N , and beneath this cock or faucet in the aisle P is a trap, O , which allows the water to escape down through the said trap and the pipe o , thus preventing freezing and accumulation of moisture at this point in the car, which would result in much discomfort and disadvantage.

Each car-door is provided with the usual grating, R , and the central portion of the car may or may not be provided with a window, S . The grating R is closed by a lining, T , which is provided with a ventilating-opening, t , as shown in Fig. 1. Where each individual animal is provided with a trough, the hollow posts D are provided with a central partition, D' , which prevents the tangling and twisting of the weights and their cords, but throughout the structure the weights are entirely concealed by the casings of the hollow partitions D .

By reference to Fig. 2 it will be observed that in some instances I design to provide a shelf, U , which is designed to be hinged to the side of the car and may be dropped down to form a berth for the attendant, or the attendant may suspend a hammock or other swinging support for himself within the space between the heads of the two series of animals at either end of the car, where he can swing easily within the car without jarring and from which position he can leave his berth instantly and hasten directly to the head of any animal in the car

without encountering any obstruction in his passage in the car. This may be done by securing a berth to the staples $V V$, of which there should be two, one at each side of the car about centrally between the lines of the heads of the animals at one end of the car. At the upper junction of the upright standard D , which comes next the door, I also provide a staple, V' , which may be used as a hitching-ring when it is desired to take an animal out into the space in front of the mangers or feed-troughs for grooming or other purposes. Two of these staples might be provided at each opposite upper corner of the door diagonally opposite each other and the hammock suspended within this space diagonally across the space, thus avoiding the necessity of providing a staple in the central portion, which might possibly hit a horse's head as he was being led to and from the car.

By reference to Fig. 1 it will be observed that I construct this car with a view to securing the greatest amount of strength from the material used. At each end I provide two diagonal braces, $W W$, which come to a point at the bottom directly over the transom of the truck. In the center of the car I have an inverted V , composed of the two slanting timbers $95 Y Y$, the center of which is at the center of the upper portion of the car. This holds the car up at the top in the center, and the downward strain which comes upon the two diagonal pieces $Y Y$ is brought directly over the support $100 Z Z$, which are supported by the truss-rods n . From the bottom of each of these braces $Y Y$ extend upward and toward the end of the car the braces $d d$, which transmit the strain from the upper inner central portion $105 Z Z$, which are supported centrally by the truss-rods n , as above explained.

In the specification and claims I shall designate that end which comes next the open 110 space between the horses' heads and between the opening doors in each side of the car, midway between the center and the end of the car, as the "rear ends." The point where we enter the stall, or the point where the partitions which divide the stalls off cease and abut against the guides for the troughs and their weights, I shall call the "open ends," while the ends of the stalls which come next the partition in the center of the car and either or 115 both of the ends of the car I shall designate as the "front ends" of the stalls. I am thus explicit on this point, because I believe that the construction of a stock-car on the plan shown and described, in which the animals are led 120 into the car and backed into the stalls, is broadly new, as heretofore the animals have been led directly into the stalls, which has necessitated much waste space within the stock-car, and which in this instance I have made 125 valuable as space for storing articles, and in which the attendant may move freely through the car in front of and about the stock.

In the aisle-space P , near the upper portion

of the car and at either side said space, I provide a series of hooks, *p p*, upon which may be hung harness, saddles, articles of clothing, and other equipments.

5 By reference to Figs. 13 and 14 it will be observed that I use one side of my pipe *D* as a conductor of water from the water tank down to the faucet, while the other side of the pipe serves as a flue for foul air, which escapes from 10 the point *s* up into and through the pipe and out of the top at *r*, which is covered by a hood. Below the point *s* the pipe is broken away and is adapted to register with a perforation, 15 *s'*, which allows the waste water to escape through the perforation and through the bottom portion of that side of the pipe which forms the flue for the escape of the foul air.

By reference to Fig. 14 it will be observed that the side *s'*, through which the water is 20 conducted, would come next to the side of the stall in the car, which would make it difficult to get the water out of this portion *s'* through the faucet out into the aisle space. I overcome this difficulty by a curved pipe, *t'*, as shown 25 more clearly in Fig. 14.

By reference to Fig. 11 it will be observed that the locking-key *J* has an inclined side, *j*. By pivoting this key on an eccentric the trunnion of the trough *E* will crowd the locking-key *J* back a sufficient distance to allow the 30 trunnion to pass through the slot underneath the locking-key *J*, when said key will by its own gravity drop back into position over the trunnion, where it will remain and prevent 35 the trough from accidental displacement vertically.

The hollow uprights *D*, provided with a central partition, *D'*, are of great advantage to the car in that they add strength to the car 40 without materially adding to its weight.

It is obvious that pivotal bars, or bars which are not pivoted, might be used in place of my cables *a a*, which would in a measure effect the same purpose which is effected by the use 45 of these cables, without departing from the spirit of my invention. It is also obvious that the troughs may be removable from the rear ends of the stalls, or they might be hinged to be pivotally moved to and from position at the 50 rear ends of the stalls, without departing from the spirit of my invention, and I do not wish to be understood as limiting myself to the exact construction of trough in this connection.

A great advantage of the construction shown 55 and described lies in the fact that by means of the construction hereinbefore described an admirable system of ventilation is secured, in that air is admitted and allowed to freely circulate through the spaces in the car between 60 the animals, directly in front of them, without exposing them to drafts from the rear or side.

From the foregoing it will be observed that in a car constructed on the plans which I have described and shown there will be a clear uninterrupted space in front of every animal, and there will be also a clear uninterrupted 65 gangway from any animal in the car to any

other animal in the car, which will enable the attendant to hasten from one animal to the other to quiet them or to adjust any of the fixtures, or to perform any services which might be required should the stock become excitable or nervous from any cause whatever, at the same time affording him ready and easy access to every animal to feed and water the animal without the necessity of the attendants climbing over any partitions or crawling through any doors or gates, as is necessary in getting from one portion of the car to the other in the cars now in use.

Having now described the objects, uses, and advantages of my device, what I desire to secure by Letters Patent, and what I therefore claim, is—

1. In a stock-car, the main body provided with stalls at the end of the car, in combination with series of stalls in the central portion of the car, the said stalls being provided with feed-troughs at the open ends, substantially as described, whereby the stock will stand face 90 to face on opposite sides of the space, substantially as specified.

2. In a stock-car, the main body provided with stalls and sliding troughs situated at the open ends of the said stalls, substantially as 95 described, whereby the loading of the car is effected by backing the stock into the stalls.

3. In a stock-car of the character described, the combination of the main car-body, the stalls situated therein, and troughs at the rear 100 of said stalls, substantially as and for the purposes hereinbefore described.

4. In a stock-car, the main body provided with stalls, in combination with hitching-cables and troughs at the rear of said stalls, substantially as and for the purposes specified.

5. In a stock-car of the character described, the main body having stalls at each end, which are provided with troughs at their rears, and central stalls provided with troughs which 110 come directly in front of the troughs of the stalls at the ends of the car, in combination with doors provided with ventilators which open into the aisle space between the troughs, all constructed substantially as described, 115 whereby a ventilating current or draft may be secured directly through the car in front of the stock without liability of a direct draft on the rear or sides of the stock, substantially as and for the purposes specified.

6. In a stock-car, the combination, with the main car-body, of the stalls located at either end and in the center of the said car-body in such a manner that aisle-spaces will be left between the end stalls and the center stalls, 125 and a communicating aisle between the said aisles.

7. In a stock-car of the character described, the main body provided with a series of stalls at each end, which are provided with troughs 130 at their open ends, and central series of stalls located within the main body, in combination with an aisle-space which extends along the central portion of the car, forming a clear and

uninterrupted passage-way from the feed-trough of any animal within the car to the feed-trough of any other animal within the car, substantially as and for the purposes specified.

8. In a stock-car, the combination of the series of stalls at each end of the car, extending entirely across the same, and central series of stalls the sides of which terminate a suitable distance from the side of the car, so as to leave a passage-way between the end series of stalls, and a central partition dividing the central stalls into two series facing in opposite directions, feed-troughs situated at the open ends of the said stalls, and aisle spaces between the end and the central stalls.

9. In a stock-car of the character described, the main body provided with a conical-shaped tank, substantially as described, whereby the force of the momentum of the water as the car rocks laterally is counteracted, substantially as and for the purposes specified.

10. In a stock-car, the main body provided with a series of stock-compartments, in combination with vertical hollow casings and vertically-sliding troughs provided with counterbalancing-weights which slide up and down within the hollow casings and connecting with the feed-troughs by cables passing over pulleys, said casings being provided with vertical guides, substantially as and for the purposes specified.

11. In a stock-car, the main body provided with a series of stalls, in combination with vertical hollow uprights having a central partition and sliding troughs provided with counterbalancing-weights which slide within the hollow guides each side of the central partition within the guide, substantially as and for the purposes specified.

12. In a car, the main body provided with diagonal braces at each end, coming to a point at the bottom directly over the transom of the truck, and the inverted V in the center of the sides of the car, composed of two slanting timbers, and the upright timbers crossing the diagonal ones, in combination with the truss-planks Z Z, supported centrally by the truss-rods n, all arranged substantially as shown and described.

13. In a stock-car, the main body having stock-compartments and vertical sliding trough, in combination with a pivoted locking-key having an inclined front and a vertical rear face, so that its lowermost extremity will be larger in diameter than its upper extremity, whereby the trunnion of the trough will crowd this key back and the said key automatically return to its normal position when the trunnion has passed, in the manner and for the purpose herein set forth.

14. In a car of the character described, the combination, with the main body, of the vertical post D, having a hood at the top central portion and a perforation at its lower portion, one side of which post is adapted to receive a pipe passing from the water-tank, and the other side serving as a conductor for foul air, which enters through the perforation and passes up and out through the side of the post, substantially as described.

In testimony that I claim the above as my invention I hereunto set my hand in the presence of two subscribing witnesses.

GEO. D. BURTON.

Witnesses:

LEWIS M. PAXTON,
CHARLES E. BARBER.
